GAS CHARGED REPEATER GUN

Theodore W. Spack, Webster Groves, Mo., assignor to Benjamin Air Rifle Company, St. Louis, Mo., a corporation of Missouri

Filed Sept. 4, 1962, Ser. No. 221,012

11 Claims. (Cl. 124—11)

This invention relates to gas charged repeater guns generally and to CO₂ cartridge type pellet or BB guns in particular.

The objects are to simplify the construction of guns of the indicated type so that maintenance of the operating mechanism is made easy; to provide improved means to regulate feed from the magazine to the breech end of the shot tube; to utilize movement of the shot tube to positively cut off the magazine and to operate a control valve in the CO₂ pressure supply chamber; to locate the control valve in an easily accessible place; and to provide a simple yet positive safety device.

A preferred embodiment of the improved gun which illustrates the presently preferred mechanism is shown in the accompanying drawings, wherein:

FIG. 1 is a fragmentary side elevational view of a gun incorporating the present invention;

FIG. 2 is a top plan view of the gun;

FIG. 3 is a longitudinal side view in fragmentary section showing the mechanism in cocked position, the usual stock or grip having been omitted;

FIG. 4 is a longitudinal sectional view of the stationary portion of the mechanism such as the pressure chamber block, magazine tube, CO₂ cartridge retainer in exploded view, and valve mechanism;

FIG. 5 is a longitudinal section view of the movable shot tube, hammer block and safety ring;

FIG. 6 is a sectional view seen at line 6—6 in FIG. 4;

FIG. 7 is a sectional view seen at line 7—7 in FIG. 5;

FIG. 8 is a perspective view of a portion of the stationary mechanism of FIG. 4;

FIG. 9 is a perspective view of the movable mechanism of FIG. 5;

FIG. 10 is a fragmentary perspective view of the mechanism in FIG. 9 showing the safety ring in safety position; and

FIG. 11 is a detailed view of the manner of assembly of the safety ring on the hammer block.

In FIGS. 1, 2 and 3, the preferred gun includes the usual stock or grip 12 and trigger guard 13. The stock is recessed at 14 to provide an elongated seat for an axially elongated body consisting of the chamber tube 15 and gun barrel 16 which are secured at the tapered plug 17. The chamber tube 15 is provided with a threaded socket element 18 which fits in a bore in the forepart of the stock 12 to receive the mounting screw 19 which secures the parts in assembly. The breech end of the chamber tube 15 mounts a trigger pivot block 20 which fits into a suitable recess in the stock 12 to align the parts in cooperation with the element 18. The trigger 21 has a hammer catch 22 thereon, and a suitable trigger spring 23 biases the catch finger 22 into a slot 24 in the chamber tube 15.

The breech end of the chamber tube 15 slidably receives a chamber block 25, the outer end of which is threaded at 26 to secure the retainer 27 for the CO₂ cartridge 28. The block 25 is formed with a chamber 29 to receive a valve 30 pressed onto a seat 31 by a spring 32. The spring 32 is retained by an O ring 33 at the mouth of the chamber 29, and the O ring 33 also functions to engage the neck portion 28a of the CO₂ cartridge 28 and seal the gas in the chamber 29. As the O ring 33 is easily accessible upon removing the retainer 27 it

2

makes access to the valve 30 quite easy which is a feature of this improvement.

The chamber block 25 is fixed in the chamber tube 15 by a set screw 34 (FIG. 3). This tube 15 is formed with a central tubular passage 35 (FIG. 4) and a radial passage 36 which opens thereto. An off-set parallel passage 37 receives one end of a magazine tube 38 which projects forwardly within the chamber tube 15 toward the tapered plug 17 and terminates in a side opening 39 which registers with a projectile loading port 40 in the chamber tube 15. The projectiles P (FIGS. 3 and 6) pass into the chamber block 25 to the radial passage 36 from the magazine tube 38 and are directed into the central passage 35 where a small magnetic plug 41 is positioned to arrest the leading projectile P and block the movement of following projectiles. The magnetic plug 41 thereby suspends each projectile P in the central passage 35 and also serves to draw each succeeding projectile into proper firing position so that gravity feed is not entirely relied upon to properly position the same.

Thus far the parts and components described are fixed in position, except that the trigger 21 and valve 30 are operatively movable. The block 25 is formed of a non-magnetic material in order to make the magnetic plug 41 effective. It is noted that the valve 30 has a piercing element 31a which acts to pierce the nozzle end 28b of the CO₂ cartridge when the same is assembled in the retainer 27 and the latter is screwed down upon the threads 26 of the chamber block 25 (the threads 26 being exposed beyond the breech end of the chamber tube 15).

In FIGS. 3, 5, 8, 9 and 10 there are shown certain operating parts of the assembly which comprise important features of the invention. An elongated projectile or shot tube 42 is provided with a plurality of side apertures 43 (four are shown) at the open breech end thereof, and spaced from this breech end is a hammer block 44. The hammer block 44 has a longitudinal slot 45 formed in its upper side, the slot 45 having a flat bottom surface 46 and a circumferential slot 47. The hammer block 44 is slidably received in the chamber tube 15 such that the elongated slot 45 receives the magazine tube 38 therein, and the breech end of the projectile tube 42 is received in the forward end of the chamber tube passage 35. The muzzle end 48 of the projectile tube 42 is slidably guided in a bushing sleeve 49 located at the muzzle end of gun barrel 16. In this assembly the hammer block 44 has its inner end 44a adjacent the slot 24 in the chamber tube 15 such that when in cocked position the catch 22 has its catch projection 22a engaged with such end 44a.

In FIGS. 3 and 9 the projectile tube 42 has a fixed abutment collar 50 thereon for the engagement of the drive spring 51. The opposite end of spring 51 engages a collar ring 52 slidable on the tube 42, and the ring 52 is held in abutment with a fixed collar 53 secured inside the barrel 16. Since the collar 53 is fixed, the spring 51 urges the projectile tube 42 toward the chamber block 25 through its pressure upon the fixed collar 50. It can now be appreciated that the projectile tube 42 reciprocates in the gun barrel 16, being guided in the elongated sleeve 49 at the muzzle end 48 and by the fixed abutment collar 53 intermediate its length. The breech end of the projectile tube 42 is guided in the passage 35 in the chamber block 25, and the hammer block 44 also supports and guides the tube 42.

In FIGS. 1 and 3 the chamber tube 15 is provided with an elongated slot 55 which permits the assembly of a cocking lever 56 by threading the same into a threaded socket 57 (FIGS. 9 and 10) in the side of the hammer block 44. The lever 56 is normally at the rearward end of slot 55 when the gun is not cocked, and after discharge. When

the gun is to be cocked the lever 56 is pushed against the spring 51 forwardly in slot 55 until the catch projection 22a snaps up behind the hammer block end 44a.

A safety latch 58 (FIGS. 6, 9, 10 and 11) is operatively mounted in the hammer block slot 47 and is rotatable therein by means of a lever 59 which moves in elongated slot 55 with the hammer block 44 and moves laterally into a latch slot 55a (FIGS. 1 and 3) to lock the hammer block 44 in cocked position, as when installing a CO₂ cartridge 28 to take the pressure of the projectile tube 42 off the valve 30 or prior to discharge of a projectile. The feature of the latch 58 is that a simple ring segment (FIG. 11) may be used in the slot, the ring being of the same outside diameter as the hammer block 44 so as to reciprocate with the block 44 in the chamber tube 15. Since the block 44 is formed with a slot 45 of the magazine tube 38, the latch ring is cut away for part of its circumference to permit rotary operation in circular slot 47 without projecting into the slot 45 where it would strike the magazine tube 38. Ring 58 is assembled or removed (FIG. 11) by aligning the gap space therein with the slot 47 such that the end face 60 will pass over the flat surface 46 at the bottom of slot 45 and the opposite end 61 will pass under the reduced diameter portion 62 of the hammer block 44. After assembly of the ring 58 in the manner shown in FIG. 11, slight rotation in a clockwise direction will prevent its removal until the ends 60 and 61 are again aligned as for assembly. The latch ring 58 is provided with a threaded socket 63 (FIGS. 6 and 11) to mount the latch lever 59.

The foregoing description has disclosed the preferred construction for the improved gun, and has pointed out certain features thereof which satisfy the stated objects. The operation of the improved gun is as follows:

To charge the gun with a CO₂ cartridge 28, the hammer block lever 56 is pushed forwardly (toward the gun muzzle) until the trigger catch projection 22a snaps up behind the hammer block end face 44a. A slight further push will bring the latch lever 59 opposite the radial slot 55a such that the lever 59 can be rotated thereinto to put the hammer "on safety." The retainer 27 is screwed off the threads 26 of the chamber block 25 and a CO₂ cartridge 28 is slipped into the retainer and the same is screwed back in place to force the neck 28a of the cartridge 28 against the O ring 33 and to position the nozzle 28b in alignment with the piercing element 31a of the valve 30. The safety lever 59 may then be rotated out of the safety slot 55a into alignment with the elongated slot 55. Upon actuation of the trigger 21, the compressed spring 51 drives the hammer block 44 backwardly to reciprocate the breech end of the projectile tube 42 in the passage 35 of the chamber block 25 to strike the valve 30 and drive the piercing element 31a into the nozzle 28b of the cartridge 28. This action charges chamber 29 and forces the valve 30 to seat tightly on the seat 31.

A plurality of projectiles P may now be loaded through the port 40 in the chamber tube 15 to fill the magazine tube 38. The leading projectile P will be drawn by the magnetic plug 41 into the passage 35, the gun being cocked by pushing the lever 56 forwardly to set the catch projection 22a against the end 44a of the hammer block 44. Upon trigger actuation, the spring 51 will drive the hammer block 44 rearwardly and reciprocate the projectile tube 42 such that the breech end of this tube picks off the leading projectile P and positively blocks off the radial feed passage 36 to prevent feed of the following projectiles. The leading projectile P is now trapped in the breech end of the tube 42 and the tube moves to strike and momentarily open valve 30. A charge of CO₂ gas is released into the tube 42 at the end and through the side apertures 43 to propel the projectile P through the tube 42. Since the CO₂ gas pressure is substantially greater than the power of spring 51, the valve 30 will close sharply and force the tube 42 to move forwardly suffi-

ciently to not continue to hold the valve 30 open. The same operation occurs for each succeeding projectile P.

The foregoing description has set for the features of construction and operation of the improved gun. It is pointed out that the assembly permits the easy and economical organization of parts within a single tubular casing and barrel which make the construction simple to manufacture. The arrangement of the chamber block locates the CO₂ gas control valve 30 in an easily accessible position for quick repair when needed. It is believed to be a novel feature to overlap the fixed magazine tube and reciprocating projectile tube in the hammer block to reduce the size of the gun, and to incorporate a simple ring safety catch encircling such assembly. It is another feature to utilize the momentum of a reciprocating projectile tube with a hammer block to actuate a gas valve, and to avoid the necessity for reciprocating other components as well as the retainer for the CO₂ gas cartridge. The preferred assembly for the reciprocating projectile tube affords a plurality of spaced guides to maintain the alignment of such tube for accuracy. A still further feature of the improved gun is the arrangement of a projectile locating magnetic element in the breech area of the gun where the projectile can be easily and positively captured in the projectile tube prior to release of the gas charge, and where the projectile tube positively cuts off the following projectiles and prevents gas escape so that substantially no gas loss is experienced and there is no necessity to provide seals in the magazine portions of the gun.

While the disclosure herein has been given in connection with a presently preferred embodiment, it is of course understood that certain changes or modifications may be made after understanding the principles hereof. It is, therefore, the intent to include all such changes or modifications within the scope of the invention as may be set forth in the annexed claims.

What is claimed is:

1. A pneumatic gun comprising a tubular chamber and a barrel tube fixed in axial alignment, said tubular chamber having an open end spaced from said barrel tube, a chamber block mounted in said open end of the tubular chamber and formed with an outwardly open valve cavity and a bore extending from said valve cavity axially toward said barrel tube, a projectile tube slidably mounted in said barrel tube and having a breech end supported by and movable in said bore, an elongated projectile magazine in said tubular chamber open to said chamber block to feed projectiles into said chamber block bore between said valve cavity and the breech end of said projectile tube, a valve operatively mounted in said valve cavity, pneumatic power supply means connected to said open end of said tubular chamber and normally causing said valve to remain closed, a hammer block fixed to said projectile tube and slidably in said tubular chamber, said hammer block having an elongated slot therein to receive said elongated magazine, said elongated slot guiding said hammer block in its slidable movement relative to said magazine, spring means operatively mounted in the gun and normally driving said hammer block and projectile tube out of a cocked position and in a direction to cause said breech end to strike and open said valve, said breech end picking off a projectile in said chamber block bore and cutting off following projectiles from said bore, and trigger means operable to releasably hold said hammer block in cocked position.

2. A pneumatic gun comprising an elongated tubular body with a breech end and a muzzle end, a chamber block and projectile magazine tube mounted as a unit in said body from the breech end, a projectile tube and hammer block mounted as a unit in said body also from the breech end, said chamber block having an open ended passage therein to receive one end of said projectile tube and said hammer block having an open ended slot to receive said projectile magazine tube such that said units fit together for assembly into said tubular body and said

projectile tube and hammer block are moveable relative to said chamber block, means to connect said chamber block to said body, resilient means in said body operative to urge said one end of said projectile tube into said open ended passage, and safety means for preventing projectile tube movement, said safety means comprising a rotary element on said hammer block, an angular slot in said body and an actuator extending through said slot and engaging said rotary element, said actuator being on safety in one end portion of said angular slot.

3. A pneumatic gun comprising an elongated tubular body with a breech end and a muzzle end and an elongated slot intermediate said ends, the slot having an angular end portion, a projectile tube and hammer block interconnected and forming a first unit movably carried in said body, a magazine tube and a chamber block interconnected and forming a second unit, said units being relatively movable and said hammer block having an elongated groove to receive said magazine tube therein and act to guide said units during relative movement, the groove in said hammer block having a flat portion and said hammer block having a circular slot intersecting said elongated groove, said circular slot being movable with said hammer block so as to move adjacent to and away from the angular end portion of the body slot, and a safety latch element operatively mounted in said circular slot and movable angularly relative to said hammer block without interference from said magazine tube lying in said elongated slot, said latch element having an operating lever movable in said body slot and a cut-away portion of less length than the diameter of said circular slot, said flat portion in said elongated slot reducing the diameter of one portion of said circular slot such that said cut-away portion may pass over said flat portion in mounting said latch element in said circular slot.

4. A pneumatic gun comprising: an elongated tubular body having a muzzle end and a breech end; a first unit adjacent said breech end and including a chamber block, a valve therein and a projectile magazine tube projecting from said chamber block toward said muzzle end; a second unit in said body and including a projectile shot tube with an inlet end slidably supported in said chamber block and a hammer block thereon with a groove in a side thereof to receive said magazine tube; said tubular body having an elongated slot in a side thereof adjacent said hammer block and an angularly directed end portion for said slot, spring means in said tubular body acting on one of said units to move the latter relative to said other unit and cause said projectile shot tube inlet end to slide in said chamber block in a direction to open said valve; and safety means for the gun including a rotary element carried by one of said units and a member engaged with said rotary element and extending through said body slot to the exterior, said member being engageable in the angularly directed end portion of said slot to hold said units against relative movement, said units being relatively movable with said member in said elongated side slot.

5. The gun set forth in claim 4 wherein a charged cartridge is mounted on said first unit and projects outwardly beyond said breech end of said body, and said valve is operatively retained in said chamber block by a spring and a deformable retainer, said deformable retainer acting on the cartridge as a seal against leakage past said cartridge.

6. A pneumatic gun comprising a tubular chamber open at one end, a barrel tube mounted in the opposite end of said chamber and in axial alignment therewith, a chamber block positioned in said tubular chamber adjacent said one open end of said tubular chamber, said chamber block having a valve chamber in one end opening outwardly and a first passage extending from said valve chamber inwardly toward said barrel tube and in axial alignment therewith, said chamber having a second passage opening laterally from said first passage, means in said tubular chamber for storing and directing projectiles

into said second passage in single file succession for movement into said first passage, a projectile tube axially reciprocably movable in said tubular chamber and barrel tube, means between said projectile and barrel tubes to guide said projectile tube, said projectile tube having an open breech end movable in said first passage past said second passage to receive and carry a projectile therein directed by said second passage into said first passage and close said second passage at each reciprocation, valve means in said valve chamber openable in response to impact engagement and in position to be engaged and opened by said breech end of the projectile tube in the direction of reciprocation to receive a projectile therein, pneumatic power supply means operatively mounted at said one end of the tubular chamber to discharge pneumatic power to said projectile tube each time said valve is opened and to force valve reclosure, a trigger, and trigger controlled means in said tubular chamber and barrel tube for reciprocating said projectile tube.

7. A pneumatic gun comprising an elongated tubular housing having an open breech end of enlarged diameter and a muzzle end of smaller diameter, a chamber block fixed in said breech end and formed with an exposed end opening outwardly of the breech end and having a valve cavity accessible from said exposed end and a bore open to said valve cavity and extending inwardly therefrom axially toward said muzzle end, means in said tubular housing to hold a supply of projectiles and to direct the projectiles into said bore in single file succession, a projectile tube having a projectile receiving inlet end slidable in said bore, hammer block means connected to said projectile tube and disposed in said tubular housing spaced from said chamber block, said hammer block means being adapted to slidably support said projectile tube for movement between cocked and projectile firing positions, spring means normally driving said projectile tube toward firing position, trigger means to control said hammer block and spring and movement of said projectile tube, pneumatic power supply means removably carried on said gun at said exposed end thereof to supply pneumatic power to said valve cavity for flow into said bore and the inlet end of said projectile tube, said power supply means having a gas discharge end and an adjacent neck and a valve assembly mounted in said accessible valve cavity through said breech end of said tubular housing and being adjacent said power supply means, said valve assembly including a valve element movable rearwardly toward said gas discharge end of said power supply means and forwardly toward the muzzle end to close said bore, spring means in said valve cavity adjacent said exposed open end normally urging said valve element forwardly to close said bore, an O ring retainer means for said spring means mounted in said exposed end of the chamber block in position to engage in gas sealing relation with said neck on said power supply means and to be engaged by the rearward end of said spring means and so as to be readily accessible upon removal of said power supply means, and a piercing element on said valve element directed rearwardly to pierce said gas discharge end of said power supply means and release the gas.

8. A pneumatic gun comprising an elongated tubular housing having an open breech end of enlarged diameter and a muzzle end of smaller diameter, a chamber block fixed in said breech end and formed with a valve cavity accessible from said breech end and a bore open to said valve cavity and extending inwardly therefrom axially toward said muzzle end, means in said tubular housing to hold a supply of projectiles and to direct the projectiles into said bore in a single file succession, a projectile tube having a projectile inlet end slidable in said bore, means in said tubular housing spaced from said chamber block to slidably support said projectile tube for movement between cocked and projectile firing positions, said slidable support means including a spring normally driving said projectile tube toward firing position, trigger means to

control said spring and movement of said projectile tube, pneumatic power supply means on said gun at the open breech end thereof to supply pneumatic power to said valve cavity for flow into said bore and the inlet end of said projectile tube, said pneumatic power supply means including a charged cartridge having an outlet end, and a valve assembly mounted in said accessible valve cavity through said breech end of said tubular housing, said valve assembly including a valve element movable to close said bore, spring means urging said valve element to closed position, and an O ring retainer means for said spring means, said O ring retainer means being a resilient seal to be engaged by said cartridge outlet end to prevent leakage of the power charge from said valve cavity.

9. A pneumatic gun comprising an elongated tubular body having a muzzle end and a breech end, pneumatic power supply means operatively mounted adjacent the breech end of said body, a projectile tube reciprocably mounted in said body and having an open breech end constituting a projectile inlet movable to pick-off projectiles and to actuate said power supply means, means connected between said body and projectile tube to reciprocate said tube and move said inlet to pick-off projectiles and to actuate said power supply means, trigger means on said body adapted to releasably hold said projectile tube from acting on the power supply means, projectile supply means in said body having a discharge end adjacent said projectile tube inlet in the cocked position thereof and a loading end remote therefrom, said projectile supply means discharge end passing projectiles one at a time into said body in the path of movement of said projectile tube inlet and said projectile tube inlet closing said discharge end upon picking off a projectile each reciprocation and means in said body to hold a projectile in position to be picked-off.

10. A pneumatic gun comprising an elongated tubular body having a muzzle end and a breech end, pneumatic power supply means including a block, a normally closed valve in said block and a pressurized cartridge supported in said block at one side of said valve, said supply means being operatively mounted adjacent the breech end of said body, a projectile shot tube reciprocably mounted in said body with a projectile inlet end spaced from but movable to actuate said valve into open position, means connected between said body and shot tube normally acting in a direction to reciprocate said tube to actuate said valve to

open position, trigger means on said body adapted to releasably hold said shot tube to prevent it from acting upon valve, projectile magazine means in said body including a tube having a discharge end in said block on the opposite side of said valve from said cartridge and a loading end remote therefrom, said projectile tube inlet end controlling said discharge end of said projectile magazine to pick-off a projectile each reciprocation and close said discharge end momentarily, and magnetic means in said block to hold a projectile in position to be picked-off.

11. A pneumatic gun comprising an elongated tubular body having a muzzle end and a breech end, a chamber block carried at the breech end, a gas charged container removably carried by said tubular body, a valve and a valve spring in said chamber block operatively mounted adjacent the breech end of said body, a projectile tube reciprocably mounted in said body and having a projectile inlet end movable upon reciprocation of said tube to actuate said valve, resilient means connected between said body and projectile tube to reciprocate said tube to actuate said valve, trigger means on said body adapted to releasably hold said projectile tube cocked against actuating said valve, projectile supply means in said body having a discharge end adjacent said pneumatic power supply means to deposit one projectile at a time adjacent said valve and a loading end remote therefrom, said projectile tube inlet end being open to pick-off a projectile and subsequently strike said valve and actuate the same, while closing said discharge end momentarily, and means in said chamber block to be engaged by said charged container and act as a seal against leakage out of said chamber block, said means also retaining said valve and valve spring in position.
